D. HANE

SAFETY COVER FOR ELECTRIC SWITCHES

Filed Sept. 7, 1923

David Hane
By Kay Fatten Brown,
Attorneys

UNITED STATES PATENT OFFICE.

DAVID HANE, OF PITTSBURGH, PENNSYLVANIA.

SAFETY COVER FOR ELECTRIC SWITCHES.

Application filed September 7, 1923. Serial No. 661,509.

To all whom it may concern:

Be it known that I, DAVID HANE, a citizen of the United States, and resident of Pittsburgh, in the county of Allegheny and State of Pennsylvania, have invented a new and useful Improvement in Safety Covers for Electric Switches; and I do hereby declare the following to be a full, clear, and exact description thereof.

10 My invention relates to electric switches including circuit breakers and other forms of heavy-duty circuit interrupters, and its object is to provide a switch of this character with a safety cover which shall be substantially airtight and moisture-proof, and which, at the same time, shall not interfere with the normal operation of the moving switch parts.

20 My invention is concerned particularly, although not exclusively, with oil circuit breakers of the type including a group of stationary contact members arranged in rows of three or four such members, and co-operating with vertically movable contact members which are so suspended and operated as to rise into engagement with the stationary contact members, and to descend away from the stationary contact members. In this type of circuit breaker, the fixed and 25 movable contact members are all suspended beneath a supporting frame, and are enclosed in an oil tank for the purpose of suppressing arcs. The upper portions of the fixed contact members extend above the supporting frame and are provided with terminal connectors for attaching lead-wires. These upper parts have heretofore been exposed to the air. When the exposed contact surfaces become moist it is possible 30 for an arc to jump across between the adjacent conductors, and it is also possible for an operator to touch the exposed conductors when making repairs, or when inspecting the switch. Serious accidents and loss of 35 life have frequently occurred in the operation of switches of this kind, and it is my specific object to protect such a switch by providing it with a safety cover which is so arranged as to exclude moisture and 40 which at the same time, permits the operating levers for the movable contact members to move freely in the usual manner.

45 To this end, I provide a closed box suitably molded from insulating material and 50 having a cover of special construction per-

mitting the cover to be placed on the box without disturbing the lead-wires, and in such a way as to make close joints at the points where the lead wires pass through the top of the box. I also provide, at one side 60 of the box, suitable openings to admit the switch-operating levers, and I mount upon the switch-operating levers a novel device which serves to close these openings in all positions of the operating levers. 65

For a further understanding of my invention, reference may now be had to the accompanying drawing, in which Fig. 1 is a side view, partly in elevation and partly in section, showing an oil circuit breaker of 70 a well-known type equipped with a safety cover constructed in accordance with my invention; Fig. 2 is a plan view of the safety cover; Fig. 3 is an enlarged fragmentary vertical section through a portion of the 75 cover; Fig. 4 is an enlarged elevational view of the sealing plate which closes the lever openings; Fig. 5 is a perspective view of one of the cover slides; and Fig. 6 is a detail of the spring seat block between the 80 switch arms.

In the drawing the numeral 2 indicates the usual frame of an oil circuit breaker, and the numeral 3 indicate the general construction of fixed contact members which are supported vertically in suitable seats in the frame 2, and which co-operate with movable contact members which are supported and guided for vertical movement beneath the fixed contact members by ordinary 85 means, not shown. The movable contact members are suspended by means of hangers 4 from the inner ends of levers 5 which are arranged in pairs, as best shown in Fig. 2, and are mounted to rock upon a stationary pivot indicated at 6. The upper ends of the stationary contact members 3 are provided with suitable terminals 7 for attachment to the usual lead-wires 8. The details of construction of the switch members 90 are not shown herein as these form no part in my invention. 95

Below the frame 2 the usual oil tank 9 is removably secured beneath the frame by means of eye-bolts 10 that are pivoted to 105 the front of the tank 9 and extend between the arms of bifurcated lugs 11, and are secured in position by winged nuts 12. Thumb set screws 13 are also provided at 110 the rear of the oil tank 9, and these set

- 5 screws extend through openings in the frame 2 and through openings in lugs 14 carried by the tank 9. The construction of the oil tank 9 and its suspension means are well known, and form no part of my present invention, which is concerned with the safety cover which rests upon the frame 2 and encloses the parts of the switch which project above the frame 2.
- 10 This safety cover consists of a box having side walls 15, and having a cover composed of two sections 16 and 17. The side walls of the box 15 may suitably be molded in one piece from insulating material, or may be otherwise constructed, as desired. The sections 16 and 17 of the box cover are arranged to join each other upon a central line 18, Fig. 2, and on this line the sections of the cover are provided with semi-circular 15 openings 19 which unite to enclose the lead-wires 8 of the central row of switch contacts.
- 20 The outer rows of lead-wires 8^a are received through similar divided openings, one-half of each of these openings being formed in the main cover section, while the other half is formed in a block or slide 21 which is suitably made from the same material as that composing the box and cover. The slides 21 have side ribs 22 which rest in 25 corresponding seats formed in the box cover, as shown in Fig. 3. The outer ends of the slides 21 are beveled as shown at 23 to correspond to the shape of the edges 24 of the main cover sections 16 and 17. As shown 30 in Figs. 1 to 3, the edges of the cover sections are received in tapered seats formed in the upper edges of the side walls 15. After the box is placed upon the switch, and the parts of the cover are set in position, the top of the box may be covered with a coating 35 of plastic insulating material so as to exclude air and moisture.
- 35 In the rear wall 15 of the box, I provide vertical slots 26 of proper width and spacing to receive the switch levers 5. The vertical slots 26 are so arranged as to permit the switch levers 5 to swing through their normal distance, which may be between the full-line position and the dotted-line shown 40 in Fig. 1. Carried by each pair of switch levers 5 and resting against the inner surface of the rear wall 15 of the box, is a sealing plate 27 suitably composed of the same material as the box and cover, and having openings 28 which fit around the switch levers 5. Grooves 29 may be formed in the plate 27 within each of the openings 28 and may be filled with felt or similar material indicated at 30, so as to produce a tight joint 45 between the plate 27 and the levers 5. The plate 27 carries a gasket 30^a of felt or other suitable material which rests against the rear wall 15 of the box, and is of sufficient size to enclose the openings 26 in the rear wall for all positions of the levers 5. In 50 order to press the plate 27 closely but slidably against the rear wall of the box, I provide between each pair of switch levers 5 a block 32, suitably of cast metal, having upper and lower flanges 33 that fit upon the upper and lower surfaces of the switch levers 5. The blocks 32 are secured to the switch levers 5 by means of bolts 34 and carry seats for tubes 35 which diverge toward the rear of the box and extend nearly 55 to the sealing plate 27. Springs 36 are carried by the sealing plate 27 and extend through the tubes 35 and into engagement with the blocks 32. These springs are of such size and strength as to exert considerable pressure upon the plate 27 in all positions of this plate, thereby constantly pressing the plate against the rear wall of the cover box. The spring tubes 35 may be loose on the springs 36, or hinged to the 60 blocks 32, or may be rigidly secured to the blocks 32.
- 65 The lower edges of the walls 15 of the safety box are shaped to fit in the frame 2 of the switch. In the switch shown on the drawing, the frame 2 has side flanges 37 which taper upwardly from front to rear, and the side walls of the safety box are correspondingly tapered and are curved to fit the upper edges of the flanges 37 as best 70 shown in Fig. 3. Strips of felt, or the like, may be secured to the lower edges of the safety box to produce a close joint with the flanges 37. The lower corners of the rear wall of the box are cut away to fit the side flanges 37 of the frame. The front and rear walls of the box extend to the upper surface of the frame body, as shown at 38 in Fig. 3, and may be provided on their lower edges with strips of felt or the like.
- 75 The eye-bolts 10 and the thumb set screws 13 are employed for securing the safety box in place, and for this purpose the box is provided with bifurcated lugs 39 to rest upon the lugs 11 of the frame at the front of the box, and with similar lugs 40 which rest upon the frames at the rear of the box, adjacent to the usual openings 41 through which the thumb set screws 13 extend. Suitable 80 gaskets may be placed between the lugs 11 and 39 and beneath the lugs 40.
- 85 In applying the safety cover to the switch, the switch levers 5 are disconnected from the hangers 4 and are passed through the openings 26 in the rear of the box and through 90 the opening 28 in the plates 27. The blocks 32 and the springs 36 are then placed in position, the switch levers 5 are attached to the hangers 4 and the bolts 10 and the screws 13 are secured in place. The lead-wires 8 are attached to the terminals 7 of the switch members 3, and the sections of the cover are then put on the safety box 3, the 95 sectional construction of the cover enabling the cover sections and the slides 31 to be 100

fitted closely around the lead wires 8. The top coating 25 of insulating material may be then applied.

5 The safety box described above effectively excludes air and moisture from the parts of the switch which extend above the frame, but do not interfere in any way with the normal operation of the switch.

10 It will be understood that the principles of my invention may be employed in constructing safety covers for switches of many different types, and that the details of construction herein shown may be varied in many respects without departing from my invention as set forth in the appended claims.

I claim as my invention:

1. The combination with an electric switch box provided with a plurality of terminals and conductors leading therefrom, of 20 a safety box comprising a casing having side walls adapted to be engaged and be closed by said switch box, and with a removable cover made in two sections having openings formed at their meeting edges for 25 some of said conductors, and also having openings adjacent to their outer edges, and slides for closing said last-named openings, the said slides and the adjacent portions of said cover sections also being formed with 30 conductor receiving openings.

2. The combination with an electric switch provided with a switch box and a cover plate therefor, for supporting a plurality of terminals and conductors leading therefrom, of 35 a safety box comprising a casing having side walls adapted to engage and be closed by said cover plate, and having a removable cover made in two sections with a row of conductor receiving openings formed at their 40 meeting edges.

3. A safety cover for electric switches comprising a box having a vertical guide slot in one of its walls to admit a switch operating lever, a sealing plate having an 45 opening to admit said lever and adapted to close said opening in all positions of said lever, and resilient means interposed between said lever and said plate for constantly pressing said sealing plate against 50 said wall.

4. A safety cover for electric switches comprising a box having a vertical slot in one of its walls to admit a switch operating lever, a sealing plate resting slidably against 55 said wall adjacent to said slide, an endless gasket carried by said plate and adapted to surround said slide in all positions of said lever, an opening formed in the said plate to admit the said lever, sealing means surrounding said last-named opening, and springs adapted to be carried by said lever for pressing said plate against the wall of 60 said box in all positions of said lever.

5. A safety cover for electric switches comprising a box having a pair of vertical

slots formed in one of its walls to admit switch-operating levers, a block adapted to be mounted between the said levers, a sealing plate resting slidably against the said wall, an endless gasket carried by said plate and adapted to close said openings in all positions of said plate, openings formed in the said plate to receive the said levers, sealing means surrounding the said openings, and springs extending between the said block 70 and the said plate and acting to press the said plate against said wall in all positions of said plate and said levers.

6. A safety cover for electric switches comprising a four-sided box having an open lower side and having its lower edge shaped to conform to a switch frame, said box having a sectional cover provided with lead-wire receiving openings at its meeting edges, and also provided with other openings for admitting lead-wires, slides for closing the said last-named openings, said slides and the adjacent portions of said cover sections being provided with lead-wire receiving openings, a pair of vertical slots formed in one 80 wall of said box to admit switch operating levers, a block adapted to be carried between said levers, a sealing plate resting slidably against the wall of said box, an endless gasket carried by said sealing plate and 85 surrounding said slots in all positions of said plate, openings formed in said sealing plate to admit the said switch levers, sealing means surrounding each of said openings, and spring extending between said 90 block and said plate and tending to force said plate against the wall of said box.

7. The combination with an electric switch box provided with a plurality of terminals and conductors leading therefrom, of a 100 switch box comprising a casing having one side removable and formed of sections which have openings formed at their meeting edges to admit conductors, and provided in one of its walls with an opening through which an operating lever may pass, a shiftable plate covering said opening, and adapted to surround the operating lever, and means for 105 yieldingly holding said plate in engagement with the last mentioned wall.

8. The combination with a switch frame and terminals carried thereby, of cover structure for said terminals, comprising a lower casing member below said frame, an upper casing member, a single means for 110 clamping the casing members in fixed relation to said frame, the upper casing member being provided with separable cover plates, each having semicircular openings that cooperate with similar openings in the other, to accommodate conductors leading to said 115 terminals.

In testimony whereof I, the said DAVID HANE, have hereunto set my hand.

DAVID HANE.
